(57) **CLAIM**

The design of a fuel nozzle, as shown and described.

DESCRIPTION

FIG. 1 is a side perspective view of an embodiment of a fuel nozzle;

FIG. 2 is a right side view of the fuel nozzle of FIG. 1;

FIG. 3 is a left side view of the fuel nozzle of FIG. 1;

FIG. 4 is a front view of the fuel nozzle of FIG. 1;

FIG. 5 is an underside rear view of the fuel nozzle of FIG. 1;

FIG. 6 is a top end view of the fuel nozzle of FIG. 1;

FIG. 7 is an underside-end view of the fuel nozzle of FIG. 1;

FIG. 8 is an underside-perspective view of the fuel nozzle of FIG. 1;

FIG. 9 is an underside-rear-perspective view of the fuel nozzle of FIG. 1; and,

FIG. 10 is a top-end-perspective view of the fuel nozzle of FIG. 1.
